(57) **CLAIM**

The ornamental design for a lamp, as shown and described.

DESCRIPTION

FIG. 1 is a perspective view of the lamp;

FIG. 2 is a top plan view of the lamp;

FIG. 3 is a bottom view of the lamp;

FIG. 4 is a side elevation view of the lamp;

FIG. 5 is an opposite side elevation view of the lamp;

FIG. 6 is an end view of the lamp; and,

FIG. 7 is an opposite end view of the lamp.

Shading shown in the figures is for illustrative purposes to show surface contours in the drawings only and forms no part of the invention.

The broken line disclosures in FIGS. 1 and 2 represent a portion of the lamp which forms no part of the claimed design.
